SCOOP-CONTROL MEANS FOR MATERIAL LOADERS

Harold M. Stueland, East Moline, Ill., assignor to Deere & Company, Moline, Ill., a corporation of Illinois

Original application March 29, 1951, Serial No. 218,105, now Patent No. 2,679,943, dated June 1, 1954. Divided and this application March 21, 1952, Serial No. 277,763

8 Claims. (Cl. 214—140)

This application is a division of co-pending application, Serial No. 218,105, filed March 29, 1951, now Patent No. 2,679,943, and the invention relates to bucket- or scoop-control means for material loaders. More particularly, the invention pertains to a tractor-mounted loader of the type useful on farms for handling manure, gravel and other materials.

A typical tractor-mounted loader comprises a machine in which the tractor provides a base on which are pivoted the rear ends of a pair of forwardly extending lift booms. The pivot of the booms to the tractor is on a transverse horizontal axis so that a bucket or scoop or equivalent load-carrying element at the front ends of the booms may be raised and lowered. The pivotal connection between the bucket and the front ends of the booms is likewise on a transverse horizontal axis about which the bucket is movable from a normal level position to a downwardly and forwardly sloping dumping position. Conventional design requires that some form of releasable latch be used between the front ends of the booms and the bucket so that the bucket may be released for tilting to its dumping position. On the other hand, it is desirable that means be provided for association with the bucket and the booms for maintaining the level position of the bucket during raising and lowering of the booms; that is to say, this means prevents rearward tilting of the bucket as the booms are raised, which would occur if the bucket is fixed to the booms. Therefore, conventional parallel linkage or other compensating means may be used for stabilizing or maintaining the level position of the bucket.

This invention relates to the coordination of bucket-release means with the bucket-leveling means. More particularly, the invention has for an object the provision of an improved and simplified construction in which the bucket may be maintained level or substantially so independently of and without affecting the operation of the bucket-release means. Conversely, it is an object to provide for operation of the release means independently of the position of the bucket relative to the ground. Primarily, it is an object to utilize bucket-release means of such nature that the means is normally of a fixed length but includes relatively movable members to produce changes in length to accomplish tilting of the bucket between its level and dumping positions.

The foregoing and other important objects and desirable features inherent in and encompassed by the invention will become apparent as a preferred embodiment of the invention is disclosed in detail in the following description and accompanying sheets of drawings.

In the drawings,

Figure 1 is a side elevational view, with the near wheels removed, of one form of loader construction in which a preferred embodiment of the invention may be incorporated;

Figure 2 is a plan view on an enlarged scale as seen along the line 2—2 of Figure 1; and

Figure 3 is a fragmentary view of a portion of the

2

forward end of the boom structure, showing the bucket in its released or dumping position.

The tractor chosen for the purposes of illustration is typical of many agricultural tractors and comprises a longitudinal body made up of an intermediate body portion 30 ahead of which is a forward body portion 32 that includes an internal combustion engine. Behind the intermediate body portion 30 is a rear body portion 34 from which conventionally project oppositely outwardly extending rear axle housings, only one of which appears at 36. A depending housing 38 is associated with the axle housing 36. A similar housing occurs at the other side of the tractor and these two housings serve to mount a pair of traction wheels, only the left-hand one of which appears at 44. The rear part of the tractor affords space for an operator and this space may be delineated at opposite sides by fenders, only one of which appears at 46.

The forward part 32 of the body includes a pair of longitudinally spaced bearings 52 and 54 between which is carried a transverse front axle structure 58. This axle structure may be of the arched type having at each side thereof a depending leg, only one of which appears at 62. This leg is provided conventionally with a spindle on which is journaled a front wheel 66. Spindle and wheel structure (not shown) has been omitted from the right-hand side of the tractor shown in Figure 1.

The tractor is completed by a forward grille structure 68 which continues rearwardly as an engine hood 70 to terminate just ahead of a steering wheel 72 for controlling the tractor front wheels 66.

The tractor may be supplemented by an auxiliary frame 78 that extends fore and aft and that has front and rear ends 82 and 84 respectively. As suggested in Figure 2, the auxiliary frame 78 is of U-shaped construction as viewed from above and has opposite side portions 88 and 90 respectively at opposite sides of the tractor.

Each of the depending housings, such as at 38, has a forwardly extending mounting bracket 96 to which is connected the rear end 84 of the proximate side portion 40 of the auxiliary frame 78. Removable securing means, such as bolts 104, may be used for effecting the connection.

The forward bearing portion 54 which supports the front axle 58 carries a depending bracket 108 to which the forward end 82 of the auxiliary frame 78 is secured. Bolts and nuts 114 and 116 may be utilized to effect the connection.

Many of the details of the loader described here form the subject matter of the patent referred to above. These 50 will be only briefly covered here for purposes of orientation.

The auxiliary frame 78 includes at its rear end and at each side thereof an upstanding support 118. The tractor, as supplemented by the auxiliary frame 78, thus provides a base for the mounting of a pair of forwardly extending, side-by-side loader or lift booms 188 and 190. Since the rear portion of only the right-hand boom 188 is disclosed, reference will be had thereto, with the understanding that the rear end of the other boom 190 is similarly mounted. The lower portion of the support 118 is provided with a pair of arcuate slots 198 and 200 and the rear portion of the boom 188 has upper and lower rollers 206 and 208 running respectively in the arcuate slots. When the booms are in their lowered positions, the rear 60 ends thereof seat with respect to the slot 200 (and with respect to a similar slot and similar support at the other side of the tractor) at a point C. The upper roller 206 is in the forward end of the upper slot 198, or is in forwardly spaced relation to the point D. The upper end of the 65 support 118 establishes a point A to which is connected a cylinder 218 forming part of a fluid motor assembly 214. The piston rod 222 of the motor 214 is connected at point 70

B to an intermediate part of the boom 188 by a suitable mounting means 234. The purpose of this arrangement is, as explained in the above-identified patent to give the lifting boom two different leverages as raising thereof is accomplished. For example, as the point B moves upwardly in the arc B⁰ to the point B¹, the basic pivot for the rear end of the boom 188 will be at the point C. At the end of the arc B⁰, or at point B¹, the upper roller 206 at the rear end of the boom seats at point D in the rear end of the upper slot 198. Point B will then travel from point B¹ through arc B^x to point B². Stated briefly, the operation gives a slow rate with maximum power during the arc B⁰ and a higher rate with less power during the arc B^x. As stated above, these details are immaterial here and need not be fully understood for the purposes of the present invention. See Patent No. 2,679,943 for further details of the boom support.

The motor 214 is of the two-way type and is contracted to cause raising of the booms. Fluid under pressure may be supplied to the motor from any suitable source (not shown) through conduits 364 and 366 via a valve 330 under control of a valve control lever 382.

The forward end of the auxiliary frame 78 may include a forwardly extending U-shaped bumper member 154 suitably joined to opposite sides 88 and 90 of the frame 78 as shown in Figure 2. The protective means afforded by the forward end of the frame 78 may further include an upstanding grille guard 168 appropriately braced at 176 to rear portions of the frame 78. These details are likewise covered in the patent referred to and need not be elaborated upon here.

Each of the lift booms has at its forward end a pivot 192 and these pivots are alined on a transverse horizontal axis for pivoting a bucket or scoop 196 to the booms. The bucket is normally carried in a level position as shown in both full and dotted lines in Figure 1 and is capable of being tilted to a forwardly and downwardly sloping dumping position as shown in Figure 3. The present invention is concerned with the control of the bucket and includes means for keeping the bucket level during raising of the booms and means for accommodating tilting of the bucket to dumping position when the booms are raised.

For the purposes of brevity and clarity, the loader is referred to as having front and rear ends. Normally this is the construction and design that will be expected. However, there are instances in which loaders are mounted at the rear ends of tractors or equivalent vehicles. Hence, directional terms should be taken herein as illustrative and not limiting.

The booms 188 and 190 carry transversely alined mounting brackets 270 and 272 respectively for the mounting between the booms of a transverse rockable element comprising transverse shaft means 268 and right- and left-hand generally upright arms 274 and 278. The arm 274 is considerably longer than the arm 278 and is welded to the shaft means 268 as at 276. The arm 278 may be welded to the other end of the shaft means 268 as at 280 (Figure 2). The upper end of the arm 274 is pivotally connected at 302 to a stabilizing or leveling link 304, the rear end of which is connected at 306 to the upper end of the upstanding support 118 at the rear of the auxiliary frame 78. Since the shaft means 268 is pivotally carried at its opposite ends respectively in the mounting brackets 270 and 272 on the booms 188 and 190, the transverse element comprising the shaft means 268 and the arms 274 and 278 may rock within limits about the axis of the shaft means as the booms are raised. The linkage connection including the links 304 comprises compensating linkage for keeping the bucket 196 level during elevation and depression of the booms, as will be brought out in greater detail below. That portion of the arm 274 between the shaft means 268 and the pivotal connection at 302 to the link 304 comprises a first lever part. That portion of the arm 274 between the shaft means 268 and a cross shaft 282 comprises a second lever part. Since the arm

278 is shorter than the arm 274, it has only the second lever part and its free end is in transverse alinement with the intermediate portion of the arm 274, whereby the transverse shaft 282 is carried at its opposite ends respectively by the two lever parts included in the arms 274 and 278 and is parallel to the transverse element 268 at the level of the upper end of the arm 278.

The transverse shaft 282 carries rotatably thereon a surrounding sleeve 284 which has welded respectively to its opposite ends two pairs of arms 286 and 288. The free or upper ends of the pair of arms 286 carry a pivot member 290 to which is connected the rear end of a forwardly extending link 292. The forward end of this link is connected at 294 to an upper portion of the bucket 196. Of importance is the fact that the pivot 294 is in vertically spaced relation to the pivot 192 between the bucket and the boom 188. The free ends of the other pair of arms 288 include a pivot 296 to which is connected the rear end of a forwardly extending link 298. The forward end of this link is connected to the other side of the bucket 196 (not shown) on an axis common with the axis of the pivot 294. For all practical purposes, the duplication of the linkage at opposite sides of the structure may be ignored, at least for the purposes of an understanding of the invention.

The linkage 286-292 and 288-298 comprises bucket-control means of normally fixed length effective between the transverse element 268-274-278 for effecting a connection between the leveling means 274-304 and the bucket 196. However, the members comprising the parts 286 and 292 are relatively movable so as to be capable of extension and retraction to effect changes in the length of the bucket-control means so that the bucket may be tilted to its dumping position. Preferably, the relationship of the members comprising parts 286 and 292 (and also the parts 288 and 298) is such as to establish an over-center lock in which the relationship of the interconnected ends of the members 286 and 292 effect a locking device relative to the transverse pivot shaft 282 (as shown in full lines in Figure 1). Thus, the bucket cannot tilt downwardly when the booms are elevated, since the line along which tensional force is exerted passes below the center of the transverse shaft 282. In effect, as long as the bucket-control means maintains its fixed length, it may be considered an extension of the leveling means, as suggested in the dotted-line position in Figure 1, wherein it will be seen that the bucket is substantially level even though the booms are materially elevated.

A sector 308 is welded to the surrounding sleeve 284 on the shaft 282 to provide a control lever for actuating the over-center lock. A control chain 310 is connected at one end to the sector 308 and extends rearwardly, passing through a guide 312 on the bracket 234 and being connected to a control rod 314 which is in turn connected to a control lever 316. This lever is pivoted at its lower end at 318 on a lower portion of the upstanding support 118.

Briefly, the operation of the loader involves only the raising and lowering of the front ends of the booms to position the bucket 196 as desired. The different leverages accomplished by the dual pivoting of the rear ends of the booms on the auxiliary frame provides for leveling the bucket through part of its raising cycle and operates to tilt the bucket slightly rearwardly in the remainder of its raising cycle, all as brought out in the above-identified patent. As long as the bucket-control means maintains its fixed length, the bucket-leveling means operate in conjunction with the bucket-control means to hold the bucket level as indicated in dotted lines in Figure 1. When the desired elevation of the bucket is achieved, the bucket-control means may be released without affecting in any respect the bucket-leveling means. Release of the bucket-control means is accomplished by a pull on the chain 310 via the control lever 316. This causes clockwise rocking of the trans-

verse pivot sleeve 284, thus breaking the over-center lock, because the arms 286 and 288 move upwardly. The reaction of the breaking of the over-center means or toggle is taken by the transverse element comprising the shaft means 268 and the arms 274 and 278. Even though the distribution of the load on the bucket may be such relative to the bucket pivot 192 as to fail to cause the bucket to tip immediately, the forward thrust delivered by the bucket-connected links 292 and 298 will effect sufficient unbalance of the bucket in a clockwise direction so that the weight of the load will complete tilting of the bucket to dumping position. The bucket is returned to its level position as the booms descend and the bucket strikes the ground, which causes the bucket to pivot in a counterclockwise direction to restore the over-center lock between the linkage 286-292 and 288-298.

Various other features of the invention not specifically enumerated will undoubtedly occur to those versed in the art, as likewise will numerous modifications and alterations in the preferred embodiment of the invention disclosed, all of which may be achieved without departing from the spirit and scope of the invention.

What is claimed is:

1. In a loader of the type having a pair of elongated booms spaced apart in side-by-side relationship and pivoted at their rear ends on a transverse horizontal axis to a base for raising and lowering of a load-carrying bucket pivoted to the front ends of the booms on a transverse horizontal axis to tilt forwardly and downwardly from a normal level position to a dumping position, the improvement comprising: a transverse rockable element spanning the booms rearwardly of the bucket and including shaft means pivoted at its opposite ends respectively on the booms on a transverse horizontal axis and having a pair of arms, one at each end of the shaft means and interconnected for angular movement in unison about the shaft means axis, one of the arms having first and second lever parts of different effective lengths having the shaft means axis as their fulcrum; element control means connected to the first lever part and to the loader base for imparting to the rockable element limited rocking movement relative to the booms as the booms are raised; and bucket control means of normally fixed length extending fore and aft between and pivotally connected at opposite ends respectively to the second lever part and to a portion of the bucket spaced vertically from the bucket axis so that limited rocking of the transverse element causes limited rocking of the bucket short of tilting of the bucket to dumping position, said bucket control means including a pair of relatively movable members connected respectively to the second lever part and to the aforesaid bucket portion, and a releasable lock device normally immobilizing the members to produce the aforesaid fixed length, said device being releasable to effect relative movement of the members to produce change in length of the bucket control means sufficient for the bucket to move to its dumping position independently of rocking of the rockable member.

2. The invention defined in claim 1, in which: said members respectively comprise links pivoted together and arranged relative to each other to effect an over-center lock; the lock device includes a control lever for breaking the over-center lock; and means is provided for mounting the control lever on the transverse rockable element.

3. In a loader of the type having a pair of elongated booms spaced apart in side-by-side relationship and pivoted at their rear ends on a transverse horizontal axis to a base for raising and lowering of a load-carrying bucket pivoted to the front ends of the booms on a transverse horizontal axis to tilt forwardly and downwardly from a normal level position to a dumping position, the improvement comprising: a stabilized transverse rockable element extending between and mounted at its opposite ends respectively on the booms on a transverse axis in

rearwardly spaced relation to the bucket and including a mounting pivot on an axis paralleling said element axis; an over-center lock device extending fore and aft between the element and the bucket and including an arm mounted on the aforesaid mounting pivot and a link connected at one end to said arm and at its opposite end to the bucket in a vertically spaced relation to the bucket pivot; and a control lever pivoted on the mounting pivot and connected to the arm for breaking the over-center lock device.

4. In a load-handling machine of the type having a base to which the rear end of a forwardly extending lift boom is pivoted on a transverse horizontal axis for vertical swinging and a load scoop is pivoted to the forward end of the boom for tilting about a transverse axis between loading and dumping position, the improvement comprising: a rock arm pivoted on the boom behind the scoop pivot, said rock arm having first and second portions spaced radially different distances from its pivot to provide respectively a long lever arm and a relatively shorter lever arm; rearwardly extending control link means pivotally connected at its forward end to one of the lever arms and pivotally connected at its rear end to the base on an axis spaced from and parallel to the pivot of the boom to the base; releasable over-center linkage connected at one end to the scoop and at its other end to the other lever arm of the rock arm, said linkage being releasable to change its length and to act on the scoop and react on the rock arm to tilt the scoop to dumping position; and means connected to and for actuating the over-center linkage.

5. In a load-handling machine of the type including a fore-and-aft extending base to which the rear ends of a pair of forwardly extending, laterally spaced apart lift booms are pivoted on a transverse horizontal axis for vertical swinging and a scoop pivoted between the forward ends of the members on a transverse axis for tilting from a carrying position to a dumping position, the improvement comprising: a transverse rockshaft carried between the booms behind the scoop; a first, relatively long arm and a second relatively shorter arm fixed to and spaced apart axially of the rockshaft and extending upwardly therefrom and parallel to each other; control link means connected between the upper end of the longer arm and a pivot on the base spaced from and parallel to the pivot of the boom to the base for stabilizing the rockshaft about its axis as the booms swing vertically; a pivot member cross-connecting the arms above and parallel to the rockshaft at the level of the upper end of the shorter arm; a sleeve journaled on the pivot member between the arms; a pair of parallel levers spaced apart and fixed to the sleeve and normally projecting rearwardly of the sleeve; a pair of links connected respectively between the levers and portions of the scoop above the pivot axis of the scoop, said links and levers providing releasable over-center means normally locked with the levers in their rearward positions to stabilize the scoop about its pivot axis via the control link means and rockshaft as the booms swing vertically; and means for rocking the sleeve on the pivot member to cause the levers to move upwardly and act forwardly through the pair of links to effect tilting of the scoop to its dumping position.

6. In a load-handling machine of the type including a fore-and-aft extending base to which the rear ends of a pair of forwardly extending, laterally spaced apart lift booms are pivoted on a transverse horizontal axis for vertical swinging and a scoop pivoted between the forward ends of the members on a transverse axis for tilting from a carrying position to a dumping position, the improvement comprising: a transverse rockshaft carried between the booms behind the scoop, a pair of parallel arms spaced apart transversely and fixed to the rockshaft and extending upwardly therefrom, one of said arms being relatively long and the other relatively short; control link means

connected between the upper end of the long arm and a pivot on the base spaced from and parallel to the pivot of the booms to the base for stabilizing the rockshaft about its axis as the booms swing vertically; a pivot member cross-connecting the arms above and parallel to the rockshaft at the level of the upper end of the short arm; a lever journaled on the pivot member and normally projecting rearwardly; a link connected between the lever and a portion of the scoop above the pivot axis of the scoop, said link and lever providing releasable over-center means normally locked with the lever in its rearward position to stabilize the scoop about its pivot axis via the control link means and rockshaft as the booms swing vertically; and means for rocking the lever on the pivot member to cause the lever to move upwardly and act forwardly through the link to effect tilting of the scoop to its dumping position.

7. In a load-handling machine of the type including a fore-and-aft extending base to which the rear ends of a pair of forwardly extending, laterally spaced apart lift booms are pivoted on a transverse horizontal axis for vertical swinging and a scoop pivoted between the forward ends of the members on a transverse axis for tilting from a carrying position to a dumping position, the improvement comprising: a transverse rockshaft carried between the booms behind the scoop; a pair of parallel arms spaced apart transversely of and fixed to the rockshaft and extending upwardly therefrom, one of said arms being relatively long and the other relatively short; means connected between the upper end of the long arm and the base for stabilizing the rockshaft about its axis as the booms swing vertically; a pivot member cross-connecting the arms above and parallel to the rockshaft at the level of the upper end of the short arm; a sleeve journaled on the pivot member; a pair of parallel levers spaced apart and fixed to the sleeve; a pair of links connected respectively between the levers and portions of the scoop above the pivot axis of the scoop,

said links and levers providing releasable over-center means normally locked with the levers in their rearward positions to stabilize the scoop about its pivot axis via the control link means and rockshaft as the booms swing vertically; and means for rocking the sleeve on the pivot member to cause the levers to move upwardly and act forwardly through the pair of links to effect tilting of the scoop to its dumping position.

- 5 8. In a loader of the class described having a load-bearing member and a loader scoop pivoted thereto for tilting between a carrying position and a dumping position, the improvement comprising: a rockable arm carried by the load-bearing member and including a short lever part and a relatively longer lever part; means connected to the longer lever part for rocking the arm; means interconnecting the shorter lever part and the scoop for transmitting rocking of the arm to the scoop to cause tilting of the scoop relative to the arm in a limited range short of dumping the scoop, said means comprising a 10 pair of pivotally interconnected links selectively relatively movable to vary the total length thereof, and a releasable over-center device normally locked with the links immobilized to serve as a force-transmitting element of fixed length between the arm and scoop; and means for 15 releasing the over-center device to provide for relative movement of the links for varying the total length thereof between the arm and the scoop to effect tilting of the scoop to its dumping position.
